UNITED STATES PATENT OFFICE.

FRED C. FRIEBE, OF BAY CITY, MICHIGAN.

VALVE-TOOL.

1,296,279.

Specification of Letters Patent. Patented Mar. 4, 1919.

Application filed September 17, 1917. Serial No. 191,859.

To all whom it may concern:

Be it known that I, FRED C. FRIEBE, a citizen of the United States of America, residing at Bay City, in the county of Bay 5 and State of Michigan, have invented certain new and useful Improvements in Valve-Tools, of which the following is a specification.

The insides of pneumatic valves, such as 10 generally provided for the inner tubes of pneumatic tires, are placed in position and removed by means of a slotted tool acting jointly with lugs provided on the valve head. One or both of these lugs frequently become 15 broken off or worn to such an extent that the tool fails to operate when it is required to remove the insides of the valve. Under these conditions recourse must had to an instrument to enable the insides of the valve 20 to be removed, but it not unfrequently happens that the use of such instruments mars the inner threads of the valve stem and is otherwise unsatisfactory in results.

This invention provides a tool which admits of placing the valve insides in position 25 and removing them from the stem both under normal and abnormal conditions and which admits of holding the valve open to provide an escape for the air when the tube 30 is required to be deflated.

For a full understanding of the invention, reference is to be had to the following description and the drawing hereto attached, in which:

35 Figure 1 is a sectional view of a valve stem and a side view of the tool illustrating the latter in position for removing the insides of the valve;

Fig. 2 is a view in elevation of the tool 40 and case therefor;

Fig. 3 is a top view of the tool and case;

Fig. 4 is a side view of the tool;

Fig. 5 is a horizontal section on the line 44 of Fig. 4;

45 Fig. 6 is a detail view of an end portion of the pin which is mounted transversely in the head of the tool;

Fig. 7 is an end view of a mutilated valve stem; and

50 Fig. 8 is a sectional detail showing one use of the tool for truing a mutilated valve stem.

Corresponding and like parts are referred to in the following description and indicated in the several views of the drawing by like reference characters.

The tool comprises a head 7, a drift 8 at one end of the head and in line therewith and a pin 16, the latter being mounted in an opening formed transversely of the head 7. The 60 pin 16 constitutes a handle for the tool and enables the same to be rotated. One end of the pin is slotted to make engagement with the head of the valve insides to admit of placing the same in position or removing 65 them from the valve stem under normal conditions. The opposite end of the pin 16 is tapered, as indicated at 15, and the extremity of the tapered end 15 is formed with a depression 15a to make positive engagement with the valve when holding the latter open to provide an escape for the air when deflating the inner tube or like part. The tapered end 15 of the pin 16 also enables the latter to be effectively used as a 70 cleaning pin for removing accumulations from the interior of the valve preparatory to re-tapping or cleaning the threads by the tapping hereinafter described. The drift 8 is tapered throughout its length and 75 of non-circular outline in cross-section, being preferably of triangular form as illustrated most clearly in Fig. 5. The corners provided at the angles of adjacent faces bite into the head of the valve insides and enable such head to be positively turned when it is required to remove a mutilated valve head which cannot be turned by the usual tool or by means of the slotted end of the pin 16. The head 7 and drift 8 are formed 80 as one part and the pin 16 is separate and retained in place in an opening formed 85 transversely through the head 7.

The numeral 10 designates the stem of an air valve such as commonly provided in 90 connection with the inner tubes of pneumatic tires. This stem 10 is formed with a bore to receive the valve insides and the upper portion of the bore is internally threaded as indicated at 14. The insides of 95 the valve are of ordinary and well known construction and comprise a head 9 which is externally threaded to match the screw-threads 14 of the stem 10. Lugs 11 are formed on the upper or outer end of the 100 head 9 to be engaged by the usual valve cap or tool generally provided for placing the valve insides in position or removing them from the stem 10 when the lugs 11 are intact. In the event of one or both of the 110 lugs 11 becoming worn or broken so as to prevent engagement of the usual tool there-

with, it is necessary to employ an instrument which may be introduced into the stem 10 and make positive engagement with the head 9 to admit of rotating such head when 5 removing the valve insides. The present tool provides for removing the insides of the valve when the usual tool fails to take hold of the head 9 and rotate the same. By introducing the drift 8 of the present tool 10 into the stem 10 and pressing the pointed end into the opening of the head 9, and giving the tool a smart blow to cause the drift to engage the head 9, the latter may be turned by rotating the tool through the 15 instrumentality of the pin 16. When the point of the drift 8 is forced into the opening of the head 9, the drift is centered in the stem 10 and is thereby prevented from injuring the threads 14.

20 From the foregoing, taken in connection with the accompanying drawing, it will be understood that the invention provides a valve tool capable of ordinary use and which enables the inside of a valve when disabled 25 to be readily removed from the valve stem without injury to the inner threads of such valve stem, the tool also embodying means for holding the valve open when it is required to deflate the inner tube or like part, 30 this being accomplished by placing the recessed end 15^a of the pin 16, on the stem of the valve and pressing the latter inward. The depression 15^a prevents slipping of the pin and the tapered end of the pin provides ample clearance for the escape of the 35 air. A suitable case 12 is provided for receiving the tool as indicated most clearly in Fig. 2, such case receiving the drift 8 and a portion of the head 7.

40 The head 7 is recessed in the end opposite that provided with the drift 8 and this recess is internally threaded, as indicated at 19, to form a die for cleaning, truing or renewing the threads at the outer end of the 45 valve stem 10. The outer end of the threaded recess is counterbored to prevent injury to the threads 19 when blows are delivered on the head 7 to force the drift 8 into the part 9.

A second pin 17 is fitted in a transverse 50 opening of the head 7 and extends at a right angle to the pin 16. One end of the pin 17 is threaded at 18 to form a tap for cleaning, truing or renewing the inner threads of the stem 10. The extremity of the tap 18 is 55 reduced at 18^a to prevent injury to the thread when striking the tap on its end to force the opposite end 17^a of the pin 17 into the opening of a mutilated valve stem 14 to true the same. (See Figs. 7 and 8.) 60

What is claimed is:

1. A valve tool comprising a cylindrical head interiorly threaded at one end and recessed beyond the threads to provide a striking edge, and a tapered drift extending longitudinally from the other end of the said head and having angularly related side faces forming edges adapted to be driven into engagement with a valve, the striking edge of the head permitting the tool 70 to be struck for driving the drift into a valve without injuring the threads.

2. A valve tool comprising a head having a transversely disposed pin extending from opposite sides of the head and tapered 75 at one end to form a truing portion and threaded at the other end and reduced beyond the screw-threads to provide a striking end to permit the truing end to be driven into a valve stem without injuring 80 the threads.

3. A valve tool comprising a cylindrical head interiorly threaded at one end and recessed beyond the threads to provide a striking edge, a drift extending from the other end of the head, the striking edge of the said head permitting the tool to be struck for driving the drift into a valve without 85 injuring the screw-threads, and a transverse cleaning pin extending from the head at 90 a point between the threads and the drift and forming a handle for the tool when driving the drift, and also when rotating the head, and the latter forming a handle for the cleaning pin in the operation of the 95 same.

In testimony whereof I affix my signature.
FRED C. FRIEBE.
